HEARING AID FOR THE HARD-OF-HEARING

Tony Gath, Roskilde, Denmark, assignor to Aktieselskabet William Demant, Copenhagen, Denmark

Filed Feb. 17, 1972, Ser. No. 227,327

Claims priority, application Denmark Sept. 10, 1971

Term of patent 14 years

Int. Cl. D24—99

U.S. Cl. D16—14 J

FIG. 7

FIG. 1 is a top plan view of a hearing aid for the hard-of-hearing, showing my new design;

FIG. 2 is a front elevation view thereof;

FIG. 3 is a bottom view thereof;

FIG. 4 is an end elevation view thereof, viewed from the left of FIG. 2;

FIG. 5 is an end elevation view thereof, viewed from the right of FIG. 2;

FIG. 6 is a rear elevation view thereof; and

FIG. 7 is a perspective view thereof, taken from the front and top of FIG. 2.

I claim:

The ornamental design for a hearing aid for the hard-of-hearing, as shown and described.
